(57) **CLAIM**

The ornamental design for a paper product dispenser, as shown and described.

DESCRIPTION

FIG. 1 is a front perspective view of a paper product dispenser showing our new design
FIG. 2 is a front view of the dispenser shown in FIG. 1;
FIG. 3 is a back view of the dispenser shown in FIG. 1;
FIG. 4 is a left side view of the dispenser shown in FIG. 1;
FIG. 5 is a right side view of the dispenser shown in FIG. 1;
FIG. 6 is a top view of the dispenser shown in FIG. 1; and,
FIG. 7 is a bottom view of the dispenser shown in FIG. 1. The dashed lines immediately adjacent to the shaded areas in the figures represent the boundaries of the claimed design. The dashed lines in the figures illustrate the portions of the design that form no part of the claimed design. None of the broken lines form any part of the claimed design.
